UNITED STATES PATENT OFFICE.

WILLIAM M. MOSIER, OF BONNER SPRINGS, KANSAS.

RAILWAY-SWITCH.

1,179,740.

Specification of Letters Patent. Patented Apr. 18, 1916.

Application filed April 9, 1915. Serial No. 20,270.

To all whom it may concern:

Be it known that I, WILLIAM M. MOSIER, a citizen of the United States, residing at Bonner Springs, in the county of Wyandotte and State of Kansas, have invented new and useful Improvements in Railway-Switches, of which the following is a specification.

This invention relates to improvements in railway switches, an object of the invention being to provide a derailer for both the main line and the siding which will be drawn into operative position when the switch is thrown, so that danger of a train traveling upon either the main line or the siding being side-wiped by a train traveling upon the other track will be effectively prevented.

Another object of the invention is to provide a derailer which will be automatically operated upon the actuation of the switch.

With the above and other objects in view, the improvement resides in the construction, combination and arrangement of parts set forth in the following specification and falling within the scope of the appended claim.

In the drawings: Figure 1 is a plan view showing the main line open, Fig. 2 is a similar view showing the main line closed to the side line, Fig. 3 is a sectional view approximately on the line 3-3 of Fig. 1, Fig. 4 is a sectional view approximately on the line 4-4 of Fig. 1, and Fig. 5 is a detail perspective view of one of the derailers.

Referring now to the drawings in detail, the numeral 1 designates the tracks of the main line, 2 the tracks of the side line, 3 the switch rails which are arranged between the main and side lines. The switch rails have their points connected by the usual bridle rod 4, and the bridle rod in the present instance extends beyond the opposite sides of the tracks. Connected to the opposite ends of the bridle rod 4, through the medium of the links 4' and 5 respectively are bell crank levers 6 and 7 respectively. The bell crank lever 6 is arranged to the opposite side of the main line and the bell crank lever 7 is arranged to the outer side of the siding.

The numerals 8 and 9 respectively designate longitudinally extending rods, each of which are preferably formed of two members connected by turnbuckles 10-10, so that the rods may be readily adjusted. The

rod 8 has its free end pivotally connected with a substantially L-shaped member 11, the said member being pivoted, as at 12, to a suitable tie or to a block arranged in the roadbed for this purpose. It will be particularly noticed that the block 12' has a base flange 13' mounted upon it, a vertical pivot being formed upon this base flange. After the derailing member has been so placed upon the block 12' that the pivot 19 will pass through its opening 12, a rivet head will then be formed upon the pivot 19 as indicated at 18'. The arm of the L-shaped lever 11, opposite that connected with the rod 8 is provided with an enlargement forming a shoe or derailer indicated by the numeral 13. The shoe is of a greater width than that of the lever proper, and preferably has its outer face provided with a longitudinally extending flange 14 and being further provided with a depending lug or stop member 15 which is adapted to contact with the outer face of the outer rail of the main line. The upper face of the said frog or derailer at its portion which overlies the said outer rail of the main line is horizontally straight, as indicated by the numeral 16 and is of course arranged at an angle with respect to the flange 14.

Fig. 4 shows the precise formation and disposition of the shoe from which it will be seen that each shoe consists of a horizontally straight flat base portion having a reduced part fulcrumed upon said pivot and disposed upon its base flange 13', whereby said base portion may pivotally move in a line with the top of the head of the rail and rest thereupon. The rod 9 likewise connects with one of the arms 17 of an angle member 18, the said angle member being pivoted, as at 19, and the second arm of the said angle member is provided with a derailer or shoe similar to that just described. It is, of course, to be understood that the shoes are arranged in reversed relation to each other; that is, arranged to permit of the shoe of the angle lever 17 swinging over the outer rail of the siding when the bridle bar is moved to open the switch to the main line and also to permit of the shoe of the said member 17 being brought out of engagement with the rail of the siding and the shoe of the member 11 brought over the outer rail of the main line when the bridle bar is moved in an opposite direction to

open the siding. The link 5 is centrally provided with an eye 20 and this eye is engaged by a depending finger 21 provided upon the turning rod 22 of a switch stand 23, the actuating lever for the said turning rod being indicated by the numeral 24 and this lever is adapted to be thrown in one of two slots or notches provided upon a circular track 25, so that the switch may be sustained in either its open or closed position. It will now be seen that the shoe is substantially L-shaped and adapted to swing with its corner projecting beyond the inner side of the rail. The longer flange is designated 14 being necessary in order to guide the particular wheel of the car to be derailed, in its movement diagonally of the length of the rail. This diagonal movement takes place as a consequence of the structure of 20 lug formed upon the shoe. This lug is formed upon the shoe diagonally of the length of the angle member 18 and it has a straight edge adapted to engage the rail to cause the shoe to be disposed diagonally of the rail.

From the above description, taken in connection with the accompanying drawings, the simplicity of the device, as well as the advantages thereof will, it is thought, be perfectly apparent to those skilled in the art to which such invention appertains without further detailed description.

Having thus described the invention, what I claim is:

In a device of the class described, in combination with a rail, a block secured along-side of said rail, a vertical pivot mounted upon said block, a derailing shoe, a base flange on said block carried by said pivot, said shoe consisting of a horizontally 40 straight flat base portion having a reduced part fulcrumed upon said pivot and disposed upon its flange whereby said base portion may pivotally move in a line with the top of the head of the rail and rest there-upon, an operating crank integrally formed upon the base portion of said shoe, means 45 engaging said arm to operate said shoe, said shoe being substantially L-shaped and adapted to swing with its corner projecting beyond the inner side of said rail, an up-standing flange formed upon one of the edges of said L-shaped shoe, and an integral depending lug formed upon said shoe diagonally of the length of said last named flange 50 and having a straight edge adapted to engage said rail to cause said shoe to be disposed diagonally of said rail.

In testimony whereof I affix my signature in presence of two witnesses.

WILLIAM M. MOSIER.
